UNITED STATES PATENT OFFICE.

CHARLES S. REES, OF SAN ANTONIO, TEXAS.

LENS-MOUNTING.

1,334,551.

Specification of Letters Patent. Patented Mar. 23, 1920.

Application filed May 18, 1918. Serial No. 235,295.

To all whom it may concern:

Be it known that I, CHARLES S. REES, a citizen of the United States, residing at San Antonio, in the county of Bexar and State of Texas, have invented certain new and useful Improvements in Lens-Mountings, of which the following is a specification, reference being had to the accompanying drawings.

- 10 This invention relates to certain improvements in lens mounting and has relation more particularly to a mounting especially designed and adapted for use in rimless eyeglasses and it is an object of the invention 15 to provide a mounting having novel and improved means whereby the lens is materially relieved from the effects of a jar or strain which would otherwise have a tendency to break the lens.
- 20 It is also an object of the invention to provide a novel and improved mounting of this general character including a strap having its marginal portions defined by inwardly directed braces or flanges whereby the strap 25 has a rigid and non-yielding formation and wherein the box like structure is produced in which a marginal portion of a lens is seated.

- 30 A still further object of the invention is 35 to provide a novel and improved mounting embodying a strap having its marginal portions defined by inwardly directed flanges for maintaining a strap against flexure and wherein said flanges are adapted for connection with a marginal portion of a lens inserted therebetween together with a cushioning element interposed between the inner face of the strap proper and the adjacent edge of a lens to serve as a means to substantially absorb the effects of a jar or strain 40 and which also serve to prevent the strap from being drawn too tight on the lens in fitting and thereby obviating the possibility of the lens being cracked or otherwise 45 broken.

- The invention consists in the details of construction and in the combination and arrangement of the several parts of my improved lens mounting whereby certain important advantages are attained and the device rendered simpler, less expensive and otherwise more convenient and advantageous for use as will be hereinafter more fully set forth.

- 55 The novel features of my invention will hereinafter be definitely claimed.

In order that my invention may be the better understood, I will now proceed to describe the same with reference to the accompanying drawings, wherein:

60

Figure 1 is a view in elevation illustrating a lens mounting constructed in accordance with an embodiment of my invention;

Fig. 2 is an enlarged fragmentary view partly in elevation and partly in section 65 illustrating my improved lens mounting as herein embodied; and

Fig. 3 is a horizontal sectional view taken 70 through Fig. 2 with certain of the parts in elevation.

70

As disclosed in the accompanying drawings 75 1 denotes a strap of predetermined length and configuration and which is adapted to overlie an edge of a lens L at an end thereof and the longitudinal marginal portions of said strap are defined by inwardly directed flanges 2 which serve as braces whereby the strap 1 is held against flexure and thereby maintained rigid and at all times in its fixed formation so that when 80 the mounting is applied to the lens L the strap is incapable of bending so that the possibility of the lens L becoming loosened is substantially entirely eliminated. The flanges 2 at substantially their longitudinal 85 centers are provided with the transversely aligned and inwardly directed ears 3 each of which having an opening 4 alining with the opening 5 produced in the marginal portion of the lens L. Disposed through the 90 registering openings 4 and 5 is a fastening screw 6 whereby the mounting or strap is held to the lens L. The perforations 4 are so positioned relative to the strap 1 as to permit the strap to have slight limited movement about the screw 6 relative to the marginal portion of the lens. Suitably secured to the inner face of the strap 1 is a strip 7 of rubber or other elastic material and which bears directly upon the marginal portion of 100 the lens.

The strip 7 acts as a cushioning element and serves to cause the strap 1 to fit firmly and rigidly to the lens without causing any strain on the lens and to absorb any shock 105 or sudden jar. It has been fully demonstrated in practice that the cushioning element as afforded by the strip 7 serves effectively to prevent breakage or cracking of the lens and to prevent the lens from becoming loose in the mounting.

My improved mounting as hereinbefore

described permits the lens to be readily interchangeable without the services of a skilled workman.

It has also been firmly established in actual practice that with a mounting constructed in accordance with an embodiment of my invention the possibility of the lens becoming loose is substantially entirely eliminated and which advantageous function 10 is materially facilitated by the brace flanges 2 as these flanges 2 make the strap 1 rigid so that it can not bend away from the lens. It is believed to be clearly obvious to those skilled in the art to which my invention appertains that as long as the strap 15 does not bend the lens can not become loose.

From the foregoing description, it is thought to be obvious that a lens mounting 20 constructed in accordance with my invention is particularly well adapted for use by reason of the convenience and facility with which it may be assembled and operated and it will also be obvious that my invention is 25 susceptible of some change and modification without departing from the principles and spirit thereof and for this reason I do not wish to be understood as limiting myself to

the precise arrangement and formation of the several parts herein shown in carrying 30 out my invention in practice except as hereinafter claimed.

I claim:

As a new article of manufacture, a mounting 35 for a rimless lens of an eyeglass, a strap disposed longitudinally on a curvature to conform to an edge portion of the lens, the longitudinal marginal portions of the strap being defined throughout their length by inwardly directed flanges serving as braces 40 to render said strap unbendable, said flanges midway their lengths being provided with transversely alined and inwardly directed ears, a holding member disposed through 45 said ears and the lens, said holding member serving as a pivot to permit the strap to have a slight limited movement relative to the marginal portion of the lens, and a strip of elastic material secured to the inner face of the strap and extending the entire length 50 thereof, said strip being constantly in contact with an edge portion of the lens.

In testimony whereof I hereunto affix my signature.

CHARLES S. REES.
